SERVICE STATION ISLAND

William F. Leppin, Jamaica, N. Y.

Application June 2, 1958, Serial No. 51,158

Term of patent 14 years

(Cl. D52—2)

Figure 1 is a perspective view of a service station island embodying my new design;

Figure 2 is an end elevation thereof, and

Figure 3 is a top plan view of the same taken on a smaller scale.

The opposite side and end of the service station island, not shown, are substantially the same as the side and end illustrated:

The essential features of my design reside in the portions shown in full lines.

I claim:

The ornamental design for a service station island, as shown and described.
